ATTORNEY

UNITED STATES PATENT OFFICE

ABE BLAUSTEIN, OF NEW YORK, N. Y.

DOLL

Application filed July 11, 1930. Serial No. 487,262.

This invention relates to new and useful improvements in dolls.

The invention has for an object the provision of a device of the class mentioned which is of simple durable construction, dependable in use and efficient in action, and which can be manufactured and sold at a reasonable cost.

The invention proposes a doll having movable eyes and mouth, a bellows cry sounder supported in the doll and exposed through an opening so as to be compressible to give out crying sounds, a lever connected with the movable mouth, a weight connected with the movable eyes and resting on said lever, and means associated with said bellows cry sounder and coactable with said lever to move the latter element for moving the mouth and eyes simultaneously with the crying operation.

The invention also proposes means for moving the eyes and mouth several times for each depression of the bellows cry sounder.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a fragmentary vertical sectional view of a doll constructed according to this invention.

Fig. 2 is a rear elevational view of Fig. 1.

Fig. 3 is a fragmentary horizontal sectional view taken on the line 3—3 of Fig. 2.

Fig. 4 is a fragmentary view similar to a portion of Fig. 1, but illustrating a modification.

Fig. 5 is a fragmentary rear elevational view of Fig. 4.

Fig. 6 is a fragmentary enlarged sectional view taken on the line 6—6 of Fig. 5.

Fig. 7 is a front elevational view of Fig. 1.

A doll has been shown on the drawing having movable eyes 10 and a movable mouth 11, a bellows cry sounder 12 supported in the doll and exposed through an opening

13 so as to be compressible to give out crying sounds, a lever 14 connected with the movable mouth, a weight 15 connected with the movable eyes 10 and resting on said lever 14, and means associated with said crying bellows 12 and coactable with said lever 14 to move the latter element for moving the mouth 11 and eyes 10 simultaneously with the crying operation.

The doll may be of any conventional design and construction. As shown on the drawing it is provided with a head portion 16 of composition material connected with a paper body portion 17. The only requisite is that the doll be hollow so as to accommodate the mechanism. The movable eyes 10 may be of any type. As shown, they comprise a pair of eye ball members provided with lashes 18 and extending through openings 19 in the head of the doll. A rod 20 is connected across the rears of the eye ball members so as to firmly hold these parts. The rod 20 is supported by a fork bracket 21 attached upon a guide support portion 22 having support plates 23 extended at the free ends into the inner sides of the doll's head. A spring 24 acts against the rod 20 and against the bracket 21 for normally urging the eye balls firmly against the opening 19.

The movable mouth 10 comprises a portion which is separate from the head and pivotally mounted at 25 upon the main portion of the head. This mouth portion includes a portion of the chin of the doll so that when operated simulates talking or crying. The bellows cry sounder 12 may be of any conventional design and construction as used in crying dolls. A rigid bracket 26 is attached to the rear of the cry sounder 12 and to the interior of the body portion 17 for supporting the cry sounder in the opening 13. This supporting allows the front of the cry sounder to be depressed inwards for causing crying. The lever 14 is attached at its top end upon the movable mouth 11 and has its circular portion arched so as to extend through the neck of the doll into the body. The weight 15 is attached upon a rod 27 extended upwards and rigidly attached to the rod 20 of the eye ball members. A cork

point 28 is attached upon the front end of the weight 15, and it is this portion which rests against the lever 14.

The means associated with said bellows cry sounder 12 and coactable with the lever 14 to move the latter element for moving the mouth and eyes simultaneously with the crying operation comprises a rigid strip 29 attached to the front of the bellows cry sounder 12 10 and extended upwards across the front of the lever 14. A peg 30 projects from the free end of the strip 29 and extends through a slot 31 formed in the lever 14. When the cry sounder 12 is depressed, the strip 29 moves 15 so as to pivot the lever 14 to move the jaw and at the same time raise the weight 15 which pivots the eye ball members 10 to simulate that the doll slightly closes the eyes during the crying.

20 In the modified form of the device illustrated in Figs. 4, 5 and 6, a means has been shown associated with the bellows cry sounder and coactable with the lever connected to the movable mouth to move the latter element 25 for moving the mouth and eyes simultaneously with the crying operation and moving the eyes and mouth several times for each depression of the bellows cry sounder. This means comprises a rack 32 attached upon the 30 front of the bellows cry sounder 12 and extended rearwards, and meshing with a gear 33 supported upon a bracket 34 attached upon the interior of the body 17. The bracket 34 supports a second gear 35 which meshes with 35 the gear 33. The spindle which supports the gear 35 extends past the bracket and is formed with a square portion indicated by reference numeral 36. A drum 37 is slidably mounted upon the square portion 36.

40 The drum 37 has one end section which supports a plurality of equally spaced short pins 38. These pins are pivotally mounted at their inner ends upon the drums and normally maintained in radial positions by coaxial springs 39 upon the pivot points. Shoulders 40 are formed on the pins 38 so as to limit movements of the pins in one direction to the radial, and allowing pivoting of the pins on their hinge points in the other 45 direction only. Another section of the drum 37 supports a large pin 41 which is pivotally mounted at its bottom end. A coaxial spring 42 is arranged upon the hinge point of the latter mentioned pin so as to normally urge it into the radial position. This pin is also provided with a shoulder 43 for limiting movement to the said radial position. A means is provided for holding the drum 37 upon the square portion 36 so that 50 one section of the drum, as for instance the section supporting the pins 38, is directly in line with the lever 14 from the mouth of the doll, or holding the drum in another position so that the pin 41 is in line with the lever 55 14.

The latter mentioned means comprises a fork 44 slidably mounted upon the inside of the body 17 by engaging a support bracket 45. The end of the slide portion of the fork 44 extends from the support bracket 45 and projects through an opening 46 in the body 17 to the exterior. This extended end is indicated by reference numeral 47. A block 48 is attached upon the inside of the body 17 70 and supports a spring 49 provided with pins 50 engageable against the extended end 47 of the fork for holding the fork as required. In Fig. 5 one of the pins is shown holding the fork so that the drum 37 is in the position in which the pin 41 is in line with the lever 14. The end 47 may be manually moved so that the other pin 50 engages it to hold the drum 37 in the position with the pins 38 in line with the jaw lever 14. 75

80 When the bellows cry sounder 12 is depressed to cause it to operate, this motion will be transmitted to move the rack 32 and rotate the drum 37. In the condition of the device as shown in Fig. 5, the large pin 41 will act against the lever 14 for smartly moving the lever outwards to cause one large movement of the jaw and a material closing of the eyes, and then drop the jaw lever 14 so that the mouth may close and the eyes open even though the bellows 12 is further depressed. In the position of the drum 37 in which the pins 38 are in line with the jaw lever 14, depression of the bellows 12 causes rotation of the drum 37 so that the fingers 38 move the jaw lever 14 and drop the latter element each 100 time a pin 38 moves past the jaw lever. This causes the mouth and the eyes to move several times during the compressing of the bellows and one single crying operation. When the bellows is released, the fingers 38 merely idle back past the jaw lever 14. 105

110 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A doll having movable eyes and mouth, a bellows cry sounder supported in the doll and exposed through an opening so as to be compressible to give out crying sounds, a lever connected with the movable mouth, a weight connected with the movable eyes and resting on said lever, and means associated with said bellows cry sounder and coactable with said lever to move the latter element for moving the mouth and eyes simultaneously with the crying operation, and moving the eyes and mouth several times for each depression of the bellows cry sounder. 120 125 130

2. A doll having movable eyes and mouth, a bellows cry sounder supported in the doll and exposed through an opening so as to be compressible to give out crying sounds, a lever connected with the movable mouth, a weight connected with the movable eyes and resting on said lever, and means associated with said bellows cry sounder and coactable with said lever to move the latter element for moving the mouth and eyes simultaneously with the crying operation, and moving the eyes and mouth several times for each depression of the bellows cry sounder, comprising a rack attached to the front of the cry sounder and meshing with a gear system connected with a drum supporting a plurality of fingers capable of individually engaging said jaw lever in succession.
3. A doll having movable eyes and mouth, a bellows cry sounder supported in the doll and exposed through an opening so as to be compressible to give out crying sounds, a lever connected with the movable mouth, a weight connected with the movable eyes and resting on said lever, and means associated with said bellows cry sounder and coactable with said lever to move the latter element for moving the mouth and eyes simultaneously with the crying operation, and moving the eyes and mouth several times for each depression of the bellows cry sounder, comprising a rack attached to the front of the cry sounder and meshing with a gear system connected with a drum supporting a plurality of fingers capable of individually engaging said jaw lever in succession, the fingers on said drum being arranged in sections of different sizes, and a means being provided for holding the drum in adjusted positions so that the different sections of fingers may act as desired against the jaw lever.

In testimony whereof I have affixed my signature.

ABE BLAUSTEIN.
